ATTORNEY

UNITED STATES PATENT OFFICE.

VICTOR CLIFFORD, OF TULSA, OKLAHOMA.

METHOD OF SEALING OIL-STORAGE TANKS.

1,266,407.

Specification of Letters Patent. Patented May 14, 1918.

Application filed February 27, 1917. Serial No. 151,303.

To all whom it may concern:

Be it known that I, VICTOR CLIFFORD, a citizen of the United States, residing at Tulsa, in the county of Tulsa and State of Oklahoma, have invented new and useful Improvements in Methods of Sealing Oil-Storage Tanks, of which the following is a specification.

This invention relates to means for improving the condition of storing, handling and protecting crude oil and other inflammable gaseous fluids, by hermetically sealing the tank in such manner as to prevent the loss of the fluid contained therein, either by ignition from outside sources caused by the tank being charged with static electricity, or evaporation caused by the escape of vapors through the many openings in the roof around the angle iron at the top of the roof and through other various openings in the tank.

I attain the foregoing objects by an improved method and means set forth in the accompanying specification, illustrated by the drawing and pointed out with particularity in the annexed claims.

In the drawing:

Figure 1 is a side elevation of the upper portion of a tank having the top arranged thereon in accordance with the present invention.

Fig. 2 is a detail vertical longitudinal sectional view through a portion of the tank and cover showing the manner of sealing the joint preparatory to the arrangement of the binder around the joint, and also illustrating the manner of covering the securing elements or nails to seal the openings made thereby,

Fig. 3 is a substantially similar sectional view through the complete joint, and

Fig. 4 is a detail perspective view of the binder.

Referring now to the drawing in detail the numeral 1 designates the tank which has its upper end or mouth provided with a continuous angle iron or cornice 2. The numeral 3 designates the wooden sheathing for the top of the tank and 4 the metal cover or closure which is designed to rest upon the sheathing and the cornice or angle iron and to be secured thereto.

In order to hermetically seal the tank, the metal top or closure 4 is first removed in order that repairs may be made to all joints or warped places in the tank caused by the

contraction and expansion. The metal closure or top 4 is then replaced, the same, resting directly upon the sheathing 3 and is secured to the said sheathing by headed galvanized nails 5. All of the joints between the cover and tank including nail holes and other openings in the tank, the gage holes, pipe lines and winch box, are protected by a fire retarding gas and acid resisting plastic cement which is indicated by the characters 6. This cement is not susceptible to the elements and being gas, acid or sulphur proof provides a lasting sealing composition. The cement is composed of asbestos fiber, creosote oil, oakum and asphaltum, and as shown by the drawing the same is cemented directly over and into the opening between the roof and shell of the tank.

After I have properly sealed the opening around the angle iron I then place in position a specially prepared connection between the roof and tank to protect the cement composition around the corners. This connection or binder is indicated broadly by the numeral 7 and comprises inner and outer sheets of wire mesh, 8-8, the same being of a desired length and width, and preferably the same is formed from a single sheet being bent upon itself centrally to form the said inner and outer faces 8. Between the faces 8 is interposed a sheet of fireproof material, such as asbestos 9, which has been previously treated with asphaltum in order to render the same gas tight, while arranged longitudinally between one of the facings 8 and the asbestos 9 are spaced wire members or rods 10 and 11 respectively. The rod 11 is arranged adjacent to one of the edges of the member 7, both the said rods having their ends passed outwardly through the asbestos sheet and through the outer facing of the wire mesh and one of the said projecting ends of each of the said rods 10 and 11 is bent upon itself to provide eyes 12 and 13 respectively. The opposite ends of the rods provide what I will term tongues and are indicated by the characters 14 and 15 respectively. The member 7 is treated to a coating of some suitable preservative material, such as asphaltum, as indicated by the numeral 16, which material is of a nature not to interfere with the electric conducting quality of the member 7.

The member 7 is of a length to surround the tank and the closure for the tank and to permit of its ends lapping around both

the tank and the closure. The upper edge of the member 7; that is, the edge thereof opposite that provided with the wire or rod 11 is arranged around the edge of the top 5 or closure 4, as illustrated in Figs. 1 and 3 of the drawings, and secured to the said top or closure by nails 17, the heads of the said nails being protected by the cement 6. The wires or rods 10 and 11 then have their ends which I have termed the 10 tongues and indicated by the characters 14 and 15 passed through the ends of the said wires or rods provided with the eyes 12 and 13 respectively, the said tongues being drawn 15 through the eyes to tightly compress the member 7 around the underedge of the cornice and around the tank 1 below the cement 6, below the cornice, the tongues being then bent over the eyes and over the rods or wires 20 from which they are formed, as illustrated in Fig. 1 of the drawing. The member 7 is designed not only to protect the cement 6 at the joint between the tank and the top therefor, but is also in the nature of an 25 electric conductor and is designed to protect and ground the tank electrically, should the same be charged with static electricity.

The cement or sealing composition 6 is a 30 non-conductor of electricity and the member 7, in the process of manufacture, is rendered soft and pliable so that the same may be easily attached to the roof and to the tank.

It is a proven fact that the fire hazard to 35 oil tanks is primarily caused by the electric currents when tank is charged with static electricity, jumping from one metal to another, and as the member 7 is a conductor of electricity and is also composed of non-inflammable fire-retarding material, the 40 same will safely conduct the electric current from the roof to the tank, and as the cement employed is of a fireproof nature and capable of resisting the influence of gas or 45 acids, it will be noted that I have provided a simple, cheap and efficient method and

means for hermetically sealing the contents of gaseous fluid containing tanks and for protecting the said contents against danger of fire, evaporation or other losses.

50

Having thus described the invention, what I claim is:

1. In combination with a metallic storage tank for gaseous fluids, having a cornice receiving the metallic cover thereof and a 55 plastic cement of fire-retarding, gas and acid resisting non-electric conducting material arranged between the cornice and the cover of the tank, of a binding element for retaining such plastic material on the tank, 60 said binder surrounding the outer edge of the cover and the cornice of the tank and made up of a wire mesh, a sheet of asbestos associated with the mesh, and a coating of preservative electric conducting material, 65 rod members passing through said binding, eyes on the ends of the rods and said eyes designed to receive the opposite ends of the rods, whereby said last mentioned ends may be bent upon themselves to effect in retaining the sheathing upon the tank.

2. In combination with a metallic storage tank for gaseous fluids, including a cover extending over the mouth of the tank, and a plastic cement arranged between the cover 75 and the outer end of the tank, of a binder for compressing and holding said plastic material against the tank, comprising a wire mesh centrally bent upon itself to provide inner and outer faces, a sheet of fire proof 80 material between said faces, a coating of preservative electric conducting material for the binder, spaced wire rods extending longitudinally between the faces of the binder, eyes on one of the ends of each rod, tongues 85 on the other end of said rods, and said tongues designed to be received in the said eyes, whereby to compress the binder against the tank and to effect in retaining the said binder on the tank.

In testimony whereof I affix my signature.
VICTOR CLIFFORD.
